CLAIM

The ornamental design for a shoe outsole, as shown and described.

DESCRIPTION

FIG. 1 is a photographic front perspective view of a shoe outsole showing my new design;

FIG. 2 is a bottom view thereof;

FIG. 3 is a rear perspective view thereof;

FIG. 4 is an enlarged view of the photographic area shown in FIG. 1;

FIG. 5 is an enlarged view of the photographic area shown in FIG. 2; and,

FIG. 6 is an enlarged view of the photographic area shown in FIG. 3.

The broken lines immediately adjacent to the photographic area illustrate the bounds of the claimed design and form no part thereof. The broken lines showing the remainder of the shoe are for environmental purposes only and form no part of the claimed design.
